UNITED STATES PATENT OFFICE.

WILLIAM W. WHITAKER, OF GLOVERSVILLE, NEW YORK, ASSIGNOR OF ONE-HALF TO DANIEL S. HULETT, OF SAME PLACE.

MITTEN.

SPECIFICATION forming part of Letters Patent No. 241,838, dated May 24, 1881.

Application filed April 15, 1881. (No model.)

To all whom it may concern:

Be it known that I, WILLIAM W. WHITAKER, a citizen of the United States, residing at Gloversville, in the county of Fulton and State of New York, have invented certain new and useful Improvements in Mittens; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention consists of a mitten having a two-ply wrist, single-ply back, and single-ply front or palm, and single-ply thumb, all knit in a continuous piece, and the palm and thumb covered with leather.

In the accompanying drawings, Figure 1 represents the knit blank for the mitten. Fig. 2 is a view of the leather palm, thumb, and border-pieces ready to be attached to the knit blank. Fig. 3 shows the finished mitten, and Figs. 4 and 5 are detached views or sections.

In the manufacture of my improved mitten, I first knit a blank, Fig. 1, with the hand A, wrist B, and thumb H all in one continuous piece, the wrist being double length, in order to be folded inward, and thus make a two-ply wrist. Then the palm-leather A' is cut and

the edge a is overstitched, and the border-pieces E and F attached and overstitched at one edge, as shown at G in Fig. 2; also the leather thumb H' is first made wrong side out, by a through-and-through stitch, and then attached to the palm-leather A' by a double seam or through-and-through stitch. Now, the leather is all ready to be attached to the knit blank, Fig. 1. The palm-leather and border-strips are first united by a through-and-through stitch, which is done while the leathers are turned wrong side out. Then the palm-leather A' and border-strips E and F and thumb-leather H' are placed on the knit blank, all being right side out, and the leather attached to the knit blank by any suitable stitch, but most conveniently by a machine, (and a through-and-through stitch,) the arm of the machine working inside of the mitten and carrying the needle and feed.

Having thus described my invention, I claim—

A mitten having a two-ply wrist, single-ply back, single-ply palm, and a thumb, all knit in one continuous piece, substantially as set forth.

WILLIAM W. WHITAKER.
